HAIR WINDER

Nathan L. Solomon, Brooklyn, N. Y.

Application July 23, 1936, Serial No. 92,205

14 Claims. (Cl. 132—41)

The subject matter of the present invention is an improved conveniently manipulatable hair curling device having rotatable clamping components for initially gripping a portion of hair and adapted to wind remaining portions of the gripped hair upon bodily rotation about the longitudinal axis thereof and in respect to a resilient and compressible locking member mounted on a hair confining member and in respect to a bearing swingably carrying the hair confining member. The objects, features and advantages of the invention may be best understood from an understanding of the following specification considered in the light of the accompanying drawing illustrating preferred embodiments thereof and wherein:

Fig. 1 is a longitudinal view partly in section of the hair winder according to the invention.

Fig. 2 shows perspective views of the manipulatable driving means disconnected from the bearing.

Fig. 3 is an enlarged sectional view taken on the line 3—3 of Fig. 1.

Fig. 4 is an enlarged sectional view taken on the line 4—4 of Fig. 1.

Fig. 5 is a view of a slightly modified form of the driver, shown partly in section.

Fig. 6 is a front elevational view of the hair winder, showing the cover raised from its companion tube and the resilient stay of the swingable loop disconnected from the tube and

Fig. 7 is a perspective view of the bearing with swingable loop unfastened thereto.

According to the invention driving means having an overhanging knurled manipulator is utilized to bodily rotate clamping components 10 and 11 of the winder generally designated 12, however, in respect to a bearing or collar 13. Particularly the aforementioned driving means is generally designated 14 (see Fig. 2) and takes the form of a substantially cylindrical bushing 15. This bushing includes a knurled head or flange 16, a shoulder 17, an annular groove or raceway 18 and the tubular shell or skirt 19 embodying diametrically disposed rivet receiving openings 20 and longitudinally and oppositely arranged grooves 21 which communicate with an annular raceway 18.

The annular bearing 13 swingably supports the hair confining member or loop generally denoted 22, the terminals 23 of which are initially passed into opposed openings 24 of the bearing 13 (see Fig. 7) so as to overhang the internal bore thereof after which the terminals are upset to provide headed members 25 (see Fig. 2) having several functions, to wit, (1), in precluding involuntary disconnection of the sides of the loop from the bearing and (2), constituting means confined within and cooperating with the sides of the annular raceway 18 of the bushing to faithfully guide

the latter during its rotation upon manipulation of overhanging flange 16. The width of the raceway is slightly greater than the width of headed members 25 and consequently the latter may be readily rotated relative to the driving means 5 when loop 22 is displaced in respect of the clamping components.

In the assembly of the bushing and bearing, the latter is placed over skirt 19 in such fashion that heads 25 of the swingable loop are disposed 10 in the opposed guide grooves 21. The bearing is then moved towards knurled flange 16 and along the skirt until it strikes flange 16. During such movement heads 25 register with the annular raceway 18 and are adapted to enter the 15 latter upon slight inwardly directed pressure applied to sides of the loop.

With the loop hingedly attached to the bearing and the latter rotatably guided on the bushing, complement or perforated tube 10 is mounted 20 on skirt 19 of the bushing, that is, one end of tube 10 is slidably moved along bushing 19 until it abuts bearing or collar 13 after which the perforated complement or cover 11 is placed over tube 10 as shown.

Forming a part of cover 11 and depending therefrom are the opposed ears 26 having alined openings 27 in registration with diametrically disposed openings 28 of the companion tube 10. Openings 28 in turn are in alinement with the opposed openings 20 of bushing 15. As illustrated a fulcrum pin or rivet 29 is utilized to pivotally hold cover 11 on the tube 10 and thus couple both of the latter to bushing 19 of the driving means 14. In this connection, rivet 29 is 35 passed through the alined openings 27, 28, and 20, of the cover, tube and bushing after which the shank of the rivet is upset to prevent accidental disengagement of these parts as is well understood.

However preparatory to coupling the hair clamping complements to the driving means, a helicoidal compression spring 30 is disposed within and transversely of the bore of skirt 19. One end of spring 30 is retained or seated in an inverted conical recess or countersunk 31 (see Fig. 1) or may be retained by a protuberance or projection 32 struck out of the body of skirt 19 (see Fig. 5). The other end of spring 30 normally extends through opening 33 in the skirt 19 50 and through alined opening 34 of tube 10 and cooperates or abuts a rearwardly disposed and slightly offset lip 35 of the hinged cover 11.

With compression spring 30 confined within the bushing and abutting the cover, and the driving means coupled to the cover and tube, the spring 30 normally holds the cover pivotally closed in respect to the tube as shown in Fig. 1. The cover may be hingedly lifted in respect to the companion tube to the position illustrated in 60

Fig. 6. In such position, lip 35 of the cover cooperates with bearing 13 which serves as a stop to limit further divergence of the cover and tube.

Loop 22 has at its forward portion a transversely disposed portion 36 interconnecting the sides 31 thereof. A spheroid or stay 38 is rotatably mounted on interconnecting portion 36 of the loop. This spheroid may be of relatively soft rubber or other suitable resilient or compressible material. With the loop swung to a locked position as shown in Fig. 1, a portion of the spheroid is telescoped within the forward end of the perforated tube and upon rotation of the latter during rotation of flange 16 of the driving means, tube 10 rotates relative the disconnectible spheroid 38.

By arranging the annular bearing between the head 16 and the tube, the bearing serves as a closure for the annular raceway, the bearing, although rotatable relative to the reduced portion or bushing of the driving means, abuts the head and tube abuts the bearing.

In operation, a fragmentary portion of the hair is first removably clamped between the hinged complements 10 and 11. This may be accomplished by disconnecting stay 38 from the tube and diverging the cover and tube to permit insertion of a fragmentary portion of hair therebetween. Manual pressure is then removed from cover 11. Consequently cover 11 automatically closes by reason of the action of spring 39 and the hair between the cover and tube is appropriately gripped.

The loop is now swung in such position to permit the stay to interlock with the forward part of the tube. Subsequently the loop is grasped by the operator. Thereafter finger pressure is applied to the knurled flange 16 to rotate the latter. Therefore the cover and tube although now clamping a part of the hair are rotated bodily and simultaneously. During such rotation, the hair clamping complements, the cover and tube, rotate relative to the stay, the loop, and the bearing. During such rotation, the hair initially gripped is wound about both the tube and cover and the sides of the loop facilitate to confine the wound hair thereabout, and it will be appreciated that although wire loop 22 is hingedly associated with bearing 13, the rear upset ends of the loop cooperates with the wall of raceway 18 of the rotatable driving means 14, consequently serving as means to faithfully guide the latter during its rotation to prevent longitudinal displacement thereof in respect to bearing 13 which is closely although movably confined between the rear end of the tube and knurled flange 16.

To remove the wound hair, the stay is disconnected from the tube and the loop is swung rearwardly. With a slight finger pressure upon the wound hair, the latter may be bodily moved towards the forward part of the tube, and be free of the latter and its companion cover.

Having now described my invention what I claim is:

1. In combination, a bearing, a bushing having an annular raceway, a loop swingably connected to said bearing and having relatively enlarged terminals disposed in said raceway for guiding displacement of said bushing relative to said bearing, hair clamping components connected to said bushing, a compressible stay mounted on said loop and adapted to removably interlock with one of said components, and compression means carried by said bushing for normally holding said complements closed.

2. In combination, a bearing, a bushing having an annular raceway, a loop swingably associated with said bearing and having relatively enlarged terminals rotatably confined in said raceway for guiding rotational displacement of said bushing in respect to said bearing, a tube mounted on said bushing, a cover mounted on said tube, means carried by said bushing for hingedly supporting said cover in respect to said tube, compressible means cooperating with said cover and bushing to normally hold said cover closed, and a stay mounted on said loop and adapted to removably interlock with said tube.

3. In combination, a bearing, a bushing having an annular raceway, a loop swingably associated with said bearing and having means projecting into said raceway for rotatably guiding rotational displacement of said bushing in respect to said bearing, a tube mounted on said bushing and abutting said bearing, a cover mounted on said tube, means carried by said bushing for pivotally supporting said cover in respect to said tube, spring means disposed within said bushing and cooperating with said cover to normally hold the latter closed, and a compressible stay rotatably mounted on said loop and adapted to removably interlock with one end of said tube.

4. In combination, a bearing, driving means comprising a head and a reduced portion including an annular raceway, a loop swingably carried by said bearing and having means projecting into said raceway for rotatably guiding displacement of said reduced portion in respect to said bearing upon manipulation of said head, a tube mounted on said reduced portion adjacent said bearing, a cover mounted on said tube, means interconnecting said reduced portion, tube and cover for pivotally supporting said cover in respect to said tube, spring means retained within said reduced portion and cooperating with said cover to normally hold the latter closed and a stay mounted on said loop adapted to removably interlock with one end of said tube.

5. In combination, an annular bearing, driving means comprising a head and a reduced portion including an annular raceway, a loop swingably carried by said bearing and having relatively enlarged means projecting into said raceway for rotatably guiding displacement of said reduced portion in respect to said bearing upon manipulation of said head, said reduced portion having means communicating with said raceway for cooperating with said enlarged means to displace said loop longitudinally of said reduced portion for disposing said enlarged means within said raceway, a tube mounted on said reduced portion, a cover mounted on said tube, means transversing said reduced portion for pivotally supporting said cover to said tube, spring means for normally holding said cover closed, and a stay mounted on said loop and adapted to removably interlock with one end of said tube.

6. In combination, an annular bearing, driving means comprising a relatively enlarged head and a reduced portion including an annular raceway, a hair confining loop swingably carried by said bearing and having relatively enlarged means projecting into said raceway for rotatably guiding displacement of said reduced portion in respect to said bearing upon manipulation of said head, said reduced portion having means communicating with said raceway for cooperating with said enlarged means to displace said loop longitudinally of said reduced portion for disposing said enlarged means within said

raceway, a tube mounted on said reduced portion, a cover mounted on said tube, fulcrum means traversing said reduced portion and overhanging the latter for pivotally supporting said cover to said tube, spring means for normally holding said cover closed, and a stay mounted on said loop for removably interlocking with one end of said tube, said bearing being rotatably mounted between said head and tube and serving as a closure for said raceway.

7. In combination, driving means comprising a manipulator including a head and a reduced portion having a raceway, a bearing abutting said head and closing said raceway, a loop swingably connected to said bearing and having means projecting into said raceway for rotatably guiding said driving means relative to said bearing, a tube mounted on said reduced portion and abutting said bearing, a cover, means carried by said reduced portion for hingedly supporting said cover to said tube, spring means for normally holding said cover closed, and a compressible stay mounted on said loop and adapted to removably interlock with one end of said tube, said tube and cover adapted to be diverged against the resistance of said spring means to permit the insertion of a fragmentary portion of hair, said driving means upon rotation thereof adapted to bodily rotate said tube and cover relative to said bearing and stay to permit remaining portions of said hair to be wound about said cover and tube.

8. In combination, rotatable driving means comprising a manipulator including a head and a relatively reduced portion having an annular raceway, an annular bearing abutting said head and movably closing said raceway, a hair confining loop swingably connected to said bearing and having means projecting into said raceway for rotatably guiding said driving means relative to said bearing, a tube having one end mounted on said reduced portion and abutting said bearing, a cover, means carried by said reduced portion for hingedly supporting said cover to said tube, spring means for normally holding said cover closed and a compressible stay mounted on said loop and adapted to removably interlock with another end of said tube, said tube and cover adapted to be diverged against the resistance of said spring means to permit the insertion of a fragmentary portion of hair, said driving means upon rotation thereof adapted to bodily rotate said tube and cover relative to said bearing and stay to permit remaining portions of said hair to be wound about said cover and tube, said loop having sides longitudinally straddling said tube and cover to closely confine the wound hair about said tube and cover.

9. In combination, a bearing, a bushing having an annular raceway, a loop swingably connected to said bearing and having relatively enlarged terminals disposed in said raceway for guiding displacement of said bushing relative to said bearing, hair grasping components connected to said bushing, and a stay mounted on said loop and adapted to removably interlock with one of said components.

10. In combination, a bearing, a bushing, a loop swingably associated with said bearing and having means rotatably guided by said bushing, a tube carried by said bushing, a cover mounted

on said tube, means carried by said tube for hingedly supporting said cover, and a stay mounted on said loop and adapted to removably interlock with said tube.

11. In combination, a bearing, a bushing having an annular raceway, a loop swingably projecting into said raceway for guiding rotational displacement of said bushing in respect to said bearing, a tube mounted on said bushing adjacent said bearing, a cover mounted on said tube, means for pivotally supporting said cover in respect to said tube, and a stay rotatably mounted on said loop and adapted to removably interlock with one end of said tube.

12. In combination, a bearing, driving means comprising a head and a reduced portion including an annular raceway, a loop swingably carried by said bearing and having means projecting into said raceway for rotatably guiding displacement of said reduced portion in respect to said bearing upon manipulation of said head, a tube mounted on said reduced portion adjacent said bearing, a cover mounted on said tube, means interconnecting said reduced portion, tube and cover for pivotally supporting said cover in respect to said tube, and a stay mounted on said loop adapted to removably interlock with one end of said tube.

13. In combination, an annular bearing, driving means comprising a head and a reduced portion including an annular raceway, a loop swingably carried by said bearing and having relatively enlarged means projecting into said raceway for rotatably guiding displacement of said reduced portion in respect to said bearing upon manipulation of said head, said reduced portion having means communicating with said raceway for cooperating with said enlarged means to displace said loop longitudinally of said reduced portion for disposing said enlarged means within said raceway, a tube mounted on said reduced portion, a cover mounted on said tube, means transversing said reduced portion for pivotally supporting said cover to said tube, and a stay mounted on said loop and adapted to removably interlock with one end of said tube.

14. In combination, an annular bearing, driving means comprising a relatively enlarged head and a reduced portion including an annular raceway, a hair confining loop swingably carried by said bearing and having relatively enlarged means projecting into said raceway for rotatably guiding displacement of said reduced portion in respect to said bearing upon manipulation of said head, said reduced portion having means disposed longitudinally thereof and communicating with said raceway for cooperating with said enlarged means to displace said loop longitudinally of said reduced portion for disposing said enlarged means within said raceway, a perforated tube mounted on said reduced portion, a perforated cover mounted on said tube, fulcrum means traversing said reduced portion and overhanging the latter for pivotally supporting said cover to said tube, and a compressible stay mounted on said loop for removably interlocking with one end of said tube, said bearing being rotatably mounted between said head and tube serving as a closure for said raceway.
